Filed May 21, 1968, Ser. No. 12,018

Term of patent 7 years

Int. Cl. D21—03

U.S. Cl. D34—15

FIG. 1 is a front elevational view of a cradle gym toy showing my new design;

FIG. 2 is a top plan view thereof;

FIG. 3 is a side elevational view thereof; and

FIG. 4 is a bottom plan view.

The essential features of my design are shown in full lines with parts of the broken line showing of the cord broken away for convenience of illustration in FIGS. 2, 3 and 4.

I claim:

The ornamental design for a cradle gym toy, as shown and described.
